UNITED STATES PATENT OFFICE

JACOB R. CARMANY, OF NEWBERRY, MICHIGAN

CLOSURE FASTENER

Application filed May 25, 1928. Serial No. 280,447.

This invention relates to an improved closure fastener, the same being particularly, but not necessarily, adapted for use in association with swinging doors, such as are employed upon sheds, garages, and the like.

The fastener is designed to prevent swinging and banging of the doors, when a car or other vehicle is leaving or entering the garage.

10 It holds the door securely closed, and prevents it from accidentally opening, as is often the case, due to a sudden gust of wind. It does away with makeshift door props, hooks and the like, and a push is sufficient to bring 15 the door to its full open position to automatically fasten the same.

I aim to provide a structure of this class, which is characterized by exceptional simplicity, of construction, and a novel organization of parts, especially constructed and cooperating to produce a dependable structure, and insuring efficient operation.

Other features and advantages of the invention will become more readily apparent 25 from the following description and drawings.

In the drawings:—

Figure 1 is a fragmentary elevational view of a door and frame bar showing the door hinged on the bar and equipped with a fastener constructed in accordance with the present invention.

Fig. 2 is a top plan view of Fig. 1, showing the relationship of parts more clearly.

35 Fig. 3 is also a top plan view showing the door swung to open position, with the fastener in a position to hold the door against closing.

Fig. 4 is an enlarged sectional and elevational view showing the manually controlling releasing means on the interior of the door.

Fig. 5 is an elevational view of a guide loop.

45 Fig. 6 is a detail view of a guide eye bracket.

Fig. 7 is a fragmentary elevational view of a slightly different embodiment of the invention.

Referring to the drawings, it will be ob-

55 the reference character 8 and the swinging hingedly mounted door by the reference character 9. On its exterior, this door is provided with a plate 10, having openings 11 and 12 adjacent its opposite ends. The openings are extended to successively receive the inturned ends 13 of a sliding latch 14. This latch is in the form of an elongated rod which extends through the eye 15, of a guide bracket 16, at one end, being connected at 60 this end to a coiled spring 17.

The spring in turn, is fastened to an anchoring bracket 18, on the frame bar. The opposite end of the rod extends through an elongated loop-like guide 19, and beyond this 65 guide, is equipped with a hand grip 20 of suitable construction. When the door is closed, as shown in Fig. 2, the inturned finger or end 13 extends through the opening 11 in the plate 10, for cooperation with the 70 release device 21.

When the door is opened, the inturned end 13, extends through the opening 12, for cooperation with the release device 22. Each device is of the construction shown in Fig. 75 4, reference being had to this figure it will be seen that the device comprises a small lever of right angular form, having one end portion 23, extending into the complementary opening in the door.

80 It is also provided with a handle portion 24, extending down through a guide eye 25. This permits the device to be manipulated in the manner to eject or force the finger 13, out of the opening in which it is located. 85 It is obvious, that with this arrangement, the casing or bearing plate 10, provides a runner, or track, upon which the finger 13, slides from one opening 11 to the other opening 12. As before intimated, when the door is closed, 90 the finger 13 is located in the opening 11. However, by pushing this finger out of the opening through the medium of the device 21, it is obvious that the door can then be swung to open position, at which time the 95 finger 13 will ride along the plate 10, and drop into the opening 12.

100 It then cooperates with the device 22 which can be manipulated for releasing it to allow the door to close again. This is plainly evi-

dent by considering Figs. 2 and 3 successively. Of course when it is desired to operate the device outside of the door, this is done by grasping the handle 20, and pulling the latch rod outwardly in an obvious manner.

5 This freedom of movement is permitted by the resilient swinging connection 17, and the elongated guide loop 19.

Referring to Fig. 7 it will be observed that 10 I employ a vertical type of spring, instead of horizontal type, as represented in Figs. 1, 2 and 3. In Fig. 7, the spring is designated by the reference character 26. One end is connected with the bracket 18, as at 27, and the 15 opposite end is connected at 28 to the rod 14. Otherwise, the structure is the same.

It is thought that by considering the description in connection with the drawing, a 20 clear understanding of the construction, operation, and advantages of the invention will be had. Therefore, a more lengthy description is regarded unnecessary.

Minor changes in shape, size, and re-arrangement of parts, coming within the field 25 of invention claimed, may be resorted to if desired.

Having thus described my invention, what I claim as new is:—

1. In a closure fastener of the class described, an apertured face plate adapted to be secured to the closure, said face plate having the apertures formed therein adapted to register with openings formed in the closure, spaced guides adapted to be secured to the 35 closure, a horizontally disposed rod slidable in said guides, said rod having an inturned end portion for successive reception in the registering apertures in said facing plate and closure, and a spring adapted to be anchored to the 40 at one end to the supporting post of the closure, the other end of said spring being secured to the opposite end of said rod.

2. In a closure fastener of the class described, a facing plate adapted to be fixed to the closure, said facing plate having apertures formed therein in registry with openings formed in the closure, guide members adapted to be mounted on said closure in longitudinal alinement with said facing plate, a rod slidable in said guides, a spring adapted to be anchored to the supporting post of said closure and having operating connection with one end of said rod, the opposite end of said rod having a laterally bent finger for selective reception in the apertures in said facing plate and closure, and a handle carried by said rod.

3. In a closure fastener of the class described, a facing plate adapted to be fixed to the closure, said facing plate having apertures formed therein in registry with openings formed in the closure, guide members adapted to be mounted on said closure in longitudinal alinement with said facing plate, a rod slidable in said guides, a spring

adapted to be anchored to the supporting post of said closure and having operating connection with one end of said rod, the opposite end of said rod having a laterally bent finger for selective reception in the apertures in said facing plate and closure, and a handle carried by said rod, together with individually manually operable release devices adapted to be mounted on opposite sides of the closure and disposed in alinement with said openings whereby said devices may be manipulated for forcing the finger out of the opening.

In testimony whereof I affix my signature.

JACOB R. CARMANY.
